UNITED STATES PATENT OFFICE.

JAMES T. WALLIS, OF ALTOONA, PENNSYLVANIA.

LUBRICATOR.

1,337,494.

Specification of Letters Patent. Patented Apr. 20, 1920.

Application filed August 9, 1919. Serial No. 316,346.

To all whom it may concern:

Be it known that I, JAMES T. WALLIS, a citizen of the United States, and residing at Altoona, Blair county, State of Pennsylvania, have invented certain new and useful Improvements in Lubricators, of which the following is a specification.

The present invention relates to a lubricating device, and more particularly to a mechanical lubricator adapted to discharge lubricant against a pressure.

According to the present invention the lubricator includes a collapsible container adapted to hold a liquid lubricant, and means to collapse the container to expel the lubricant. More particularly the container is of metal and has side walls adapted to permit the container to be collapsed. Other features of the invention reside in the means for subjecting the outside of the container to a pressure substantially equal to the pressure within the container, thus tending to oppose any distortion of the container; and the provision of means whereby the container may be charged with lubricant without removing the container from its support. Other features consist in the general combination and arrangement of the parts constituting the device.

The objects and features of novelty of the invention will be apparent from the description taken in connection with the drawings, in which—

Figure 1 is a sectional elevation through a lubricator constructed in accordance with the present invention;

Fig. 2 is a plan view, one half in section of the lubricator, the section being taken on the line 2—2 of Fig. 1;

Fig. 3 is a sectional elevation taken substantially on the line 3—3 of Fig. 2;

Fig. 4 is a view in elevation illustrating the manner of connecting the lubricator to a pressure pipe into which lubricant is to be discharged, and

Fig. 5 is a sectional view similar to Fig. 1 illustrating a modified form of the invention.

Referring to the drawings which illustrate one embodiment of the invention, the numeral 10 indicates a shell, shown as cylindrical, having one of its ends closed by a head

12, the head 11 being secured to the shell as by means of studs 13, and the head 12 being fastened to the shell by studs 14. Disposed within the shell 10 is a collapsible container 15, preferably of metal, and adapted to hold a liquid lubricant. In the form shown, the side walls of the container may be corrugated or of a shape which may be termed accordion walls, as indicated at 16. It will be seen that this construction permits the container to be collapsed like the bellows of an accordion. One end of the container is open and provided with a peripheral flange 17, which is clamped between the shell and head 11, thus securing the container to the shell. For the purpose of filling the container with lubricant, the head 11 is provided with a filling opening 18, normally closed by a plug 19. The lubricant is discharged through a conduit 20 connected as by means of pipe 21 to the point where it is desired to feed the lubricant.

For the purpose of positively collapsing the container, mechanism is disposed at the lower end of the container. As shown a nut 22 is rotatively mounted in bearings at 23 and 24 carried by the lower head 12 of the shell and a spider 41 respectively. A plate 25 is disposed under the bottom of the container, and has a stem 26 threaded through the nut 22. It will be seen when the nut 22 is rotated, the plate 25 will be moved vertically. In order to prevent rotation of the plate 25, it is provided with a peripheral lug 27 slidable in a keyway 28 formed in the interior of the shell.

Any suitable mechanism may be provided for rotating the nut 22. As shown a worm wheel 29 is connected with the nut, the nut in fact forming the hub of said wheel. A shaft 30 rotatively carried by the head 12, has a worm 31 in engagement with the worm wheel 29. For the purpose of turning the shaft 30 in either direction, a hand crank 31 may be provided. In the normal operation of the device however for collapsing the receptacle, a ratchet device is provided. As shown this device is mounted within the housing 32 rotatable on the shaft 30, the housing carrying a pawl 33 adapted to cooperate with a ratchet wheel 34 secured to the shaft 30. Thus when the arm 35 secured to the housing 32, is oscillated auto-

matically or manually, the ratchet wheel and shaft 30 will be turned in one direction, thereby gradually collapsing the container. After the container has been collapsed, it 5 may be allowed to expand by turning the hand crank 31 in the direction to lower the follower plate 25.

When the lubricator is used for the purpose of supplying lubricant to a pressure 10 pipe, the container is subjected to a considerable bursting pressure which may distort the same. According to this invention means is provided to counteract, or in a measure equalize the bursting pressure by 15 a pressure on the outside of the container. In the present case this is accomplished by connecting the pressure pipe by means of a conduit 36 to the space within the head 12, this space communicating with the space 20 between the outside of the container and the interior of the shell. Thus the pressure within the pressure pipe will be conducted to the shell 10, so that the outside of the container is subjected to a pressure very 25 nearly the same as the pressure on the interior thereof. In cases where the pipe to which the lubricant is applied is a steam pipe, some of the steam supplied to the head 12 and on the outside of the container will condense, and a drain 37 is provided to allow this condensate to run out, a valve 38 controlling the same. It is obvious that if desired this drain may be 30 opened and closed by means of the usual thermostat diaphragm, such as used in steam heating apparatus of railway cars.

In the operation of the lubricator, the plate 25 being at the lower end of its movement, the container is filled through the 40 opening 18 and closed by the plug 19. Then as the arm 35 is oscillated the follower plate 25 will be moved upward, collapsing the container and expelling the lubricant. At the same time pressure fluid from the pressure fluid pipe will be conducted to the 45 outside of the container, thereby equalizing the pressure on the interior and exterior thereof.

In the modified form of the invention 50 illustrated in Fig. 5 the general arrangement of the parts is similar to the device already described. The means for preventing leakage of lubricant when the plunger is operated, however, comprises a device 55 consisting of the end wall 40 and the collapsible side walls 16', the ends of these walls having a flange 17' secured between the shell 10 and the spider 41. The bottom wall 40 is secured to the plunger 25' in any 60 suitable manner as by means of rivets 42. It will be observed, that the collapsible device of this form of the invention is like that illustrated in Fig. 1 in that both devices have an end wall engaging the plunger, collapsible side walls and a flange at the end 65

thereof secured to the shell. In this form of the invention rotation of the plunger and its threaded rod 26' is prevented by a set screw 27' extending into the longitudinal groove 28' in the threaded rod 26'.
70

In the operation of the lubricator just described the plunger is moved to the position illustrated in Fig. 5 and the shell 10 then filled with lubricant through the opening 18. Thereafter as it is desired to force out the lubricant from the lubricator the plunger 25' is advanced in the same manner as described in connection with Fig. 1, thus expelling lubricant through the discharge passage 20. The flange 17' of the collapsible device being secured to the shell will prevent any lubricant from passing into the lower head 12. As the plunger advances the collapsible wall 16', which may be described as an accordion wall, expands to the 80 position illustrated in dotted lines near the top of the shell 10. The plunger 25' and the collapsible device are returned to the full line position shown in Fig. 5, in the same manner that the plunger is returned in the form of the invention shown in Fig. 1. Any pressure acting on the accordion walls due to forcing out the lubricant from the shell is counter-balanced by the fluid pressure acting on the opposite side of the 85 walls and introduced to the head 12 through the pipe 36. In this manner distortion of the collapsible device is prevented.
90

Although two specific forms of the invention have been described in detail, it is to 100 be understood that it is not thus limited, but includes other modifications and changes which come within the scope of the appended claims.

Having thus described the invention what 105 is claimed as new and desired to be secured by Letters Patent is:

1. A device of the character described including in combination a rigid shell, a collapsible container disposed in and secured at 110 one end to the shell, the shell having a normally closed opening through which lubricant may be supplied to the container, a discharge conduit in communication with the container, and means to collapse the latter. 115

2. A device of the character described including in combination, a cylindrical shell having one end closed, a collapsible container within said shell having an open end disposed at the closed end of the shell and secured thereto, a discharge conduit having communication with the interior of said container, said shell having a filling opening through which lubricant may be supplied to the container, and means disposed at the 120 end of the shell opposite the closed end to collapse the container and thereby expel the lubricant.
125

3. A device of the character described including in combination, a rigid shell, a con- 130

tainer having an open end disposed at one end of the shell, said container having accordion side walls whereby it may be collapsed, means closing the open end of the container having a filling opening and a discharge conduit, and means at the opposite end of the shell to collapse said container.

4. A device of the character described including in combination, a rigid shell, a collapsible container within the shell having an open end, means closing the open end of said shell having a discharge conduit, means to secure the container to the shell at its open end, and means to collapse said container.

5. A device of the character described including in combination, a shell, a cap closing one end of the shell, a collapsible container within the shell having a flanged open end, 20 said flange being secured between the shell and cap, a discharge conduit communicating with said container, and means to collapse the container.

6. A device of the character described including in combination, a shell, a collapsible metal container having one end open and formed with accordion side walls, means closing the open end of the container, means securing the container to the shell adjacent 30 the said open end, a discharge conduit communicating with said container, and means to collapse the container.

7. A device of the character described including in combination, a shell, a collapsible container within the shell constructed with springy side walls which normally hold the container distended, means securing one end of the container to the shell, and means operative on the other end of the container 40 to collapse the same.

8. A device of the character described including in combination, a shell, a collapsible container within the shell having an open end, means closing said end, a discharge conduit communicating with the container, and means to collapse the container including, a nut held against axial movement, a plate associated with the bottom of the container having a stem threaded through the 50 nut, and mechanism to turn said nut.

9. A device of the character described including in combination, a shell, a collapsible container within the shell having an open end, means closing said end, a discharge conduit communicating with the container, and means to collapse the container including, a nut held against axial movement, a plate associated with the bottom of the container having a stem threaded through the 55 nut, a ratchet device to turn the nut in the direction to collapse the container and other means to turn the nut in either direction.

10. A device of the character described including in combination, a shell, a collapsible

container within the shell having an open end, means closing said end, a discharge conduit communicating with the container, and means to collapse the container including, a nut held against axial movement, a plate 70 associated with the bottom of the container having a stem threaded through the nut, a worm wheel rotatably connected with the nut, a worm associated with the wheel and means to rotate the worm.

11. A device of the character described including in combination, a cylindrical shell closed at both ends, a collapsible container within the shell having an open end adjacent one end of the shell secured thereto, the latter end of the shell having a discharge conduit leading to a pressure pipe to which the lubricant is fed, means at the other end of the shell to collapse the container, and means providing communication between the said 85 pipe and the space between the outside of the container and the interior of the shell, whereby the outside of the container is subjected to a pressure tending to oppose distortion thereof.

12. A device of the character described including in combination, a shell having closed ends, a collapsible container within the shell having an open end secured to the shell, a discharge conduit for the container, 95 means to collapse the container and means acting on the outside of the container to oppose distortion thereof.

13. A device of the character described including in combination, a shell having 100 closed ends, a collapsible container within the shell having an open end secured to the shell, a discharge conduit for the container, means to collapse the container and means to conduct a pressure fluid to act on the 105 outside of the container to oppose distortion thereof.

14. A device of the character described including in combination, a shell having closed ends, a collapsible container within 110 the shell having an open end secured to the shell, a discharge conduit for the container, means to collapse the container, means to conduct a pressure fluid to the space between the interior of the shell and the outside of the container, and means to drain 115 said space.

15. A device of the character described including in combination, a shell having closed ends, a collapsible container within 120 the shell having an open end secured to the shell, a discharge conduit for the container, means to collapse the container and means to subject the outside of the container to a pressure substantially equal to the pressure within the container.

16. A device of the character described including in combination, a shell having closed ends, a metal collapsible container adapted to hold liquid lubricant disposed 130

in the shell having an open end secured to the shell, a discharge conduit for the container, and means to collapse the container.

17. A lubricator including in combination, a rigid shell having one end closed provided with a discharge opening, a plunger movable to and from said closed end, a device disposed within said shell comprising an end wall and longitudinally collapsible side walls, said end wall engaging the face of said plunger and the ends of the side walls opposite said end wall being secured to said shell adjacent one end thereof, and means to actuate said plunger.
18. A lubricator including in combination, a rigid cylindrical shell having one end closed provided with a discharge opening, a plunger movable to and from said closed end, a device disposed within said shell comprising an end wall and longitudinally collapsible accordion side walls, said end wall engaging the face of said plunger and the ends of the side wall opposite said end wall being secured to said shell adjacent one end thereof, and means to actuate said plunger.
19. A lubricator including in combination, a shell having closed ends, a plunger movable in said shell, a device disposed in said shell comprising an end wall and col-

lapsible side walls, said end wall associated with said plunger and the opposite ends of the side walls being secured to said shell adjacent one end thereof, means to actuate said plunger, and means to introduce a pressure fluid to act on the device to counter-balance the pressure tending to distort the same due to forcing out the lubricant. 35

20. A lubricator including in combination, a shell having closed ends, a plunger 40 within said shell, a collapsible device secured to the shell engaging the plunger to form a seal, and means to introduce a pressure fluid to act on said device to counter-balance the pressure tending to distort the 45 same due to forcing out the lubricant.

21. A lubricator including in combination, a shell having closed ends, a plunger within said shell, and a collapsible device secured to the shell engaging the plunger 50 to form a seal preventing leakage.

22. A device of the character described including in combination, a shell, a plunger therein, an endwise collapsible annular member secured at one end to the plunger 55 and at its opposite end to the shell and means for actuating the plunger.

In testimony whereof I affix my signature.

JAMES T. WALLIS.
